UNITED STATES PATENT OFFICE.

PHILLIP S. WISEMAN, OF SPRINGFIELD, OHIO.

PIPE-CO尤LING FOR RAILWAY-CARS.

SPECIFICATION forming part of Letters Patent No. 396,908, dated January 29, 1889.

Application filed December 15, 1887. Serial No. 257,968. (No model.)

To all whom it may concern:

Be it known that I, PHILLIP S. WISEMAN, a citizen of the United States, residing at Springfield, in the county of Clark and State of Ohio, have invented certain new and useful Improvements in Heating Appliances for Railway-Cars, of which the following is a specification, reference being had therein to the accompanying drawings.

10 This invention relates to certain new and useful improvements in heating appliances for steam-railway cars; and the invention consists of the peculiarities hereinafter appearing, and more fully pointed out in the claims.

15 In the accompanying drawings, forming a part of this specification, and on which like reference-letters indicate corresponding parts, Figure 1 represents a side elevation of two service-pipes, the coupling therefor, and a distributing-pipe, showing the adjacent ends of two cars in section; Fig. 2, a longitudinal sectional view of a portion of two service-pipes, with the coupling partly in section and partly in elevation; Fig. 3, a plan view of a car-floor, 25 with the sides in section, showing the arrangement of my service and distributing pipes, and showing also the adjacent ends of two service-pipes and their coupling; Fig. 4, a vertical sectional view on the line *x*-*x* of Fig. 3; Fig. 5, a similar view to Fig. 3 with change in the service-pipe; Fig. 6, a sectional view on the line *y*-*y* of Fig. 5; Fig. 7, a detail view of the service-pipe and coupling-pipe; Fig. 8, a detail view of a coupling-pipe and a clamp.

35 The letters A and B designate the adjacent ends of two railway-cars of the ordinary construction. To the bottom of each, and preferably to the under side, are attached service-pipes C and D. These pipes extend from end 40 to end of the cars, and are provided with cut-offs E, for the purpose of controlling the passage of the heating element in connection with which they are used. There are various arrangements which may be adopted for the 45 heat-distributing pipes; but I prefer substantially the arrangement shown, which consists of the pipes F, which connect with the respective service-pipes and extend along the floor of the car, near the sides and ends 50 thereof, and below the flooring at the middle portion of the ends, so as not to obstruct the

aisle, as seen at G. This cross-connection may exist at both ends of each car or only at one end, the object of which is to put the distributing-pipes at both sides of the car in 55 communication with each of the service-pipes of that particular car. This is done so that the heating element entering either service-pipe may be conducted to all the distributing-pipes, if desired, while the same may be 60 cut off by one of the cocks H. It is contemplated to use generally only one of the service-pipes of a car at a time; but two are provided on each car, so as to avoid one service-pipe being on one side of one car and the 65 other service-pipe on the other side of the other car, in case they should happen to be so turned with respect to each other. Each distributing-pipe F has connected to it a suitable number of sub-distributing pipes, I, which 70 may occupy the space under each seat, if desired.

The letters J and J' designate the coupling-pipes, each consisting of short sections having a packing at K, which snugly fits the service-pipes, respectively. Each service-pipe also has a head at L, which snugly fits the pipes J and J', respectively. A spiral spring is secured to the head L and the portions K of each pipe, the contracting force of which 75 tends to project the pipes J and J' toward each other. Each of these pipes is provided at its outer entrance with a head, M and N, respectively, substantially hemispherical in shape and hollow, so as to receive each a 80 sphere, O, and form a tight joint between them. The spheres O are also hollow, and are connected by an intervening tubular neck, P. Each sphere is constructed with an enlarged opening, Q, which communicates with 85 the pipes J and J', respectively, the latter communicating with the interior of the pipes C and D. This construction admits of a universal movement between the heads M and N and the respective spheres O, whereby the joint 90 is accommodated to the various inequalities and movements of the respective cars. The spheres are held, or further held, in the heads by means of clamps R, consisting of two prongs, 95 each of which embraces a sphere O, and connected with the heads M and N, as by a lug, S, extending therefrom and bent down firmly 100.

over the connected ends of the clamps in such a manner as to hold them firmly against the spheres. I prefer to make the clamps of steel wire and coil the ends of each branch thereof, 5 so as to form a convenient place to take hold of with the hand when it is desired to uncouple or couple the heads with the spheres. As shown in Fig. 2, it will be seen that the clamps are placed upon the opposite sides of 10 the heads. This, however, is immaterial, and each head may carry one or more clamps. The openings Q are sufficiently large to prevent cutting off the passage when the spheres are oscillated to one side or the other and up or 15 down. The action of the springs T, as already intimated, is that of forcing the heads M and N against the spheres, and also of allowing longitudinal yield when the cars approach and recede from each other.

20 So far in this description I have kept the arrangement of service-pipes shown in Figs. 1, 2, 3, and 4 distinct from the arrangement shown in Figs. 5 and 6. Referring to the latter arrangement, C' and D' designate the 25 service-pipes, which are placed under the platform and end of each car at about the middle of the width thereof, and connected with the portion G of the distributing-pipe by a branch, G'. This branch is long enough to 30 bring the service-pipe below the usual coupling, as seen at H' in Fig. 5. In this arrangement the cut-offs E are not necessary, as the cut-offs H may be manipulated to prevent the escape of the heating element and to control 35 its admission. This form is also cheaper than the other, and is therefore preferred. Again, when the pipes are placed at the center instead of at the sides of the car, there is less movement between the spheres and the hemispherical heads. The sliding sections of pipe, 40 with their hemispherical heads, are fitted to the central service-pipes in the same manner as to the side service-pipes.

I contemplate using the invention to conduct steam from one car to the other, which 45 is to be received from some suitable source, preferably from the locomotive-boiler. Hot air, however, may be conveyed from car to car by means of these improvements. I de- 50 sign to supply each end of each service-pipe with two extra spheres, the same to be attached to the car-body, as suggested in Fig. 3, so that there will always be at hand this portion of the coupling. While those of one

car are in use those of the other car remain 55 suspended by chains. I have already stated that one or both of the service-pipes of the car may be used at a time. This will be governed according to individual circumstances. The cut-offs E in the service-pipes prevent 60 the steam or hot air from escaping to the rear of the last car, and may be manipulated to prevent the escape of the steam when changing a car from one train to another.

Having thus fully described my invention, 65 what I claim as new, and desire to secure by Letters Patent, is—

1. The combination, with a car, of a heating service-pipe, a short section of pipe fitted within the same, and a spring connected to 70 the service-pipe and to said section of pipe, and tending to project the latter from the former, the said section of pipe having a hemispherical hollow head, two hollow spheres connected by an intervening neck, one of 75 which fits said head and each of which has an opening opposite the intervening neck, and a spring-clamp secured to the head and embracing the sphere within it.

2. The combination, with a central service-pipe and a tubular section slidably fitted within it and provided with a hollow hemispherical head, a packing between the service-pipe and said tubular section, and a spiral spring connected with the service-pipe 80 and section, and tending to project the latter from the former, of two hollow spheres connected together by an intervening hollow neck and having openings opposite the ends of said neck, and a spring-clamp connected 85 to each head and composed of two prongs which engage the respective spheres.

3. The combination, with a tubular section having a hollow approximately hemispherical head, and a spring-clamp secured to the head 90 and divided into two prongs, of two hollow spheres connected together by an intervening hollow neck and each having an opening in the end opposite the said neck, one of which is fitted into said head and is held by said 95 clamp.

In testimony whereof I affix my signature in presence of two witnesses.

PHILLIP S. WISEMAN.
